UNITED STATES PATENT OFFICE.

FREDERICK C. WILLIS, OF WEST NEW BRIGHTON, NEW YORK, ASSIGNOR TO WESTERN ELECTRIC COMPANY, INCORPORATED, OF NEW YORK, U. S. A., A CORPORATION OF NEW YORK.

TRANSLATING APPARATUS.

Application filed May 14, 1923. Serial No. 638,750.

This invention relates to translating apparatus, and more particularly to modulators employed in carrier current and radio signaling systems.

5 Certain objects of the invention are to provide a more efficient modulator; to provide a modulator wherein less energy of carrier frequency is required to maintain the control electrode at the optimum potential 10 for modulating purposes; to provide a balanced modulator of the electronic valve type wherein the control electrodes thereof are maintained at the proper potential with small input energy of carrier frequency; to 15 provide a modulator wherein the full force of the source of high frequency carrier oscillations is applied to the control electrode thereof.

Modulators of the electronic valve type 20 with only a single valve or two valves in balanced relation are employed in carrier current telegraph and telephone systems and in radio systems. Speech frequency currents, telegraph currents or other signaling 25 currents impressed upon the modulator interact therein with high frequency currents supplied thereto and produce modulated high frequency currents.

The modulating currents ordinarily originate 30 on a line coupled to the modulator input circuit through a transformer.

In order to prevent fluctuations of the capacity between the windings of such a transformer and ground, the core and containing 35 case of the transformer are grounded. In practice, one terminal of the heated cathode of such an electronic modulator is also grounded to prevent fluctuations in the capacity between the parts of the modulator 40 and ground.

As heretofore employed, the source of carrier frequency currents has been coupled to the modulator input circuit between the heated cathode and the modulating current 45 input transformer or other coupling.

It has been found that the capacity between the modulating current input coupling and ground, and the capacity from the incoming line and the apparatus thereof to 50 ground shunts the carrier frequency currents from the control electrode of the modulator necessitating a greater amount of input energy to maintain the control electrode at the optimum potential.

This shunting effect increases with increase in the frequency of the carrier currents, so that in high frequency carrier and radio systems, an abnormal amount of input energy is required.

In accordance with the present invention 60 the apparatus of the modulator input circuit is so organized and the carrier frequency source is so coupled thereto that such capacity to ground has no effect upon the potential of the control electrode. 65

The invention is illustrated as applied to a modulator having two electronic valves connected in balanced relation, but it is to be understood that it may be applied to other types of modulators and employed in 70 other relations.

Referring to the drawing, a pair of three-electrode electronic valves 1 and 2, each having a grounded cathode or filament heated by current from a battery or other source, 75 an anode or plate, and control electrode or grid, are provided. The valves are preferably similar and equal in their structure and characteristics.

The input circuits of the valves are arranged in parallel with respect to the secondary winding of a transformer 3 in the common conductor of the two input circuits. The primary of the transformer 3 is connected in circuit with a source 4 of high frequency oscillations. One terminal of the transformer secondary is connected to the cathodes of the valves 1 and 2, and the other terminal thereof to the rotor of a balancing 80 variable condenser 5. The stators of the condenser are connected to the respective conductors individual to the valve input circuits. 90

Condenser 5 is made variable so that the impedance of the individual paths of the input circuits may be varied to compensate for any difference in the characteristics of the two electronic valves whereby the output circuits may be maintained in balanced 95 relation with respect to the carrier frequency oscillations. 100

A source of modulating signal current variations such as, for example a transmitter 6 and a battery 7, is coupled to the valve input circuits by means of a transformer 8. 105

The transformer 8 is provided with a grounded case 9 to which the transformer core is connected. This construction stabi-

lizes the capacity which exists between transformer windings and ground.

This capacity is in parallel with the valve control electrodes and shunts the high frequency oscillations from the control electrodes unless some means is provided to prevent the shunting action.

As the frequency of the oscillations increases, the shunting action of this capacity becomes greater.

In order to overcome this shunting action and supply to the control electrodes the full force of the high frequency oscillations, the two windings of a retardation coil 10 are connected in the respective individual paths of the valve input circuits between the sources of high frequency oscillations and modulating signal current variations.

These two windings, which have a common core, are connected so as to be parallel aiding to the high frequency oscillations and series opposing to the modulating signal current variations.

With respect to the coil 10, the term "parallel aiding" refers to the fact that, for alternating currents supplied from the secondary winding of transformer 3, the windings of coil 10 provide parallel paths to ground through the distributed capacity of transformer 8. For such currents, the windings of coil 10 are so arranged as to set up magnetic fields which tend to produce in the core, on a plane intersecting the core intermediate the windings, magnetic poles which are of opposite signs. The fields may therefore be said to be mutually aiding. For such currents, the coil 10 is accordingly highly inductive and offers high impedance.

The term "series opposing" applied to coil 10 refers to the fact that current from the transformer 8 flows in series through the windings of coil 10, that is, at any given instant in one direction through one winding and in the opposite direction through the other winding. The flow of this current through the windings of coil 10 causes magnetic fields to be set up in the core such that there tends to be produced, on a plane intersecting the core intermediate the windings, magnetic poles which are of the same sign. The fields may therefore be described as mutually opposing. For such currents, the coil 10 is substantially non-inductive and offers low impedance.

These windings of the retardation coil therefore offer very low impedance to the modulating signal variations, but offer such high impedance to the high frequency oscillations as to effectively prevent the passage of such oscillations. Consequently the full force of the high frequency oscillations is impressed upon the control electrodes of the valves irrespective of the presence of the capacity from the transformer 8 to ground.

A negative polarizing potential for the

control electrodes of the valves is supplied from a battery 11 or other source.

The output circuits of the valves 1 and 2 are connected in parallel with respect to a battery 12, arranged in the common conductor of said circuits. Each output circuit contains one half of the primary winding of an output transformer 13. The secondary winding of the output transformer 13 is connected to an outgoing circuit. 75

Normally, when no signal current variations are impressed upon circuit 14, the high frequency oscillations from source 4 acting through transformer 3 impress equal voltage variations of the same phase upon the control electrodes of the valves, thereby producing equal fluctuations of the same phase in the output circuits. Since the two halves of the primary winding of the output transformer 13 are wound in the same direction, 85 the outgoing circuit 15 is differentially coupled to the two output circuits. The fluctuations therefore neutralize each other and produce no effect in the outgoing circuit. When, however, low frequency modulating signal current variations from circuit 14 are impressed upon the input circuits through transformer 8, the high frequency potential variations are augmented upon one control electrode and decreased upon the other, producing correspondingly augmented fluctuations in one output circuit and correspondingly reduced fluctuations in the other. The fluctuations in the output circuits are no longer balanced and consequently 95 oscillations are produced in the outgoing circuit 15 which have an amplitude proportionate to the instantaneous values of the low frequency modulating currents incoming from circuit 14. 105

The balanced modulator shown in the drawing constitutes a duplex translating apparatus wherein the unmodulated carrier oscillations are suppressed and the currents of frequencies within the side bands of the carrier are supplied to the outgoing circuit. 110

The modulator embodying the present invention is highly efficient in that the optimum control electrode potential is maintained with only approximately twenty per cent of the carrier frequency energy heretofore required. 115

The invention set forth herein is of course susceptible to various other embodiments and adaptations. 120

The invention claimed is:

1. In a wave translation system, a repeater, a source of signals and a source of carrier waves, individual means for coupling said sources to said repeater, and means offering a cumulative impedance to waves from one source and a differential impedance to waves from the other source included between said sources. 125

2. A translating apparatus comprising a 130

- duplex translating arrangement, parallel circuits for said translating arrangement including a common path and individual paths, conductive evacuated gaps in said individual paths, a source of high frequency oscillations associated with the common path, and the individual paths, a source of modulating signal variations associated with the individual paths, and means in the individual paths which is substantially non-inductive to current from one source and highly inductive to current from the other source to provide high impedance to the high frequency oscillations and low impedance to the modulating signal current variations.
3. A translating apparatus comprising a duplex translating arrangement, parallel circuits for said translating arrangement including a common path and individual paths, conductive evacuated gaps in said individual paths, a source of high frequency oscillations associated with the common path and the individual paths, a source of modulating signal current variations associated with the individual paths, and a retardation coil having two windings, one in each individual path, said windings being connected to be parallel aiding to the high frequency oscillations and series opposing to the modulating signal current variations.
4. A translating apparatus comprising a duplex translating arrangement, parallel circuits for said translating arrangement including a common path and individual paths, conductive evacuated gaps in said individual paths, a source of high frequency oscillations associated with the common path and the individual paths, a source of modulating signal current variations associated with the individual paths, and an inductive winding in each individual path with a common core therefor, said windings being arranged so as to offer high impedance to the high frequency oscillations and low impedance to the modulating signal current variations.
5. A translating apparatus comprising a duplex translating arrangement, parallel circuits for said translating arrangement including a common path and individual paths, conductive evacuated gaps in said individual paths, a source of high frequency oscillations associated with the common path and the individual paths, a source of modulating signal current variations associated with the individual paths, and an inductive winding in each individual path between the two sources with a core common to the windings, said windings being connected so as to be parallel aiding to the high frequency oscillations and series opposing to the modulating signal current variations.
6. The combination of an electronic valve modulator having a grounded, heated cathode, an anode, and a control electrode, an input circuit connected to the cathode and control electrode, means to couple a source of modulating currents with the input circuit, said coupling means having a capacity to ground in parallel with the control electrode, a source of currents of higher frequency coupled to said input circuit, and inductive means between said source of modulating currents and said source of currents of higher frequency which is also between said source of modulating currents and said input circuit, said inductive means being adapted to have a different inductance with respect to the currents from the said sources.
7. The combination of an electronic valve modulator having a grounded heated cathode, an anode and a control electrode, an input circuit connected to the cathode and control electrode, means to couple a source of modulating currents to the input circuit, said coupling means having a capacity to ground in parallel with the control electrode, a source of carrier currents of high frequency coupled to the input circuit and means to prevent said capacity from shunting the carrier currents from the control electrode, including a choke coil comprising a plurality of windings upon a toroidal magnetic core, said windings being arranged to be ineffective with respect to said modulating currents, and to be effective with respect to said carrier currents in magnetizing said core.
8. The combination of a modulator having two electronic valves, each having a grounded heated cathode, an anode and a control electrode, parallel input circuits for the valves including a common path connected to the cathodes and individual paths connected to the control electrodes, a source of high frequency oscillations associated with the common and individual paths, a source of modulating signal current variations associated with the individual paths, and means in the individual paths between said sources allowing the passage of the modulating signal current variations and preventing the passage of the high frequency oscillations, said means comprising a choke coil having a plurality of windings traversed by said high frequency oscillations in such manner as to offer cumulative impedance thereto.
9. A translating device having an element substantially at ground potential for high frequency currents, an input circuit for said device including means to impress thereon high frequency currents and means to impress thereon low frequency currents, and means comprising a choke coil having two windings on a single core adapted to be inductive with respect to said high frequency currents to prevent the high frequency currents from being dissipated thru the capacity to ground of said low frequency impressing means.
10. In a wave translation system, a space

discharge tube, a source of high frequency waves and a source of signal waves applied thereto, means for coupling said sources to said tube having a capacitive path tending 5 to divert high frequency energy from said tubes, and means in series with said path comprising a two-winding coil on a single core offering high impedance to high frequency waves and low impedance to signal 10 waves.

11. In a wave translation system, a plurality of space discharge tubes, sources of signal waves and high frequency waves connected to said tubes by means having a path 15 including a capacity in shunt to the high frequency source tending to reduce the high frequency voltage applied to said tubes, and means, in said path, which is non-inductive

for current from one of said sources but offers high impedance to waves from said 20 other source.

12. In a wave translation system, a plurality of space discharge tubes in push-pull relation, a source of signals and a source of carrier waves connected to said tubes, a 25 transformer for said signal source which provides an inherent capacity path in shunt to said carrier wave source, said path including leads in a series circuit including said transformer and said tubes, and a 30 choke coil connected to said leads in such manner as to be non-inductive to signal waves and inductive to carrier waves.

In witness whereof, I hereunto subscribe my name this 27 day of March A. D., 1923.

FREDERICK C. WILLIS.
